UNITED STATES PATENT OFFICE.

EDWARD C. MEHLECK, OF ALBANY, NEW YORK.

CHECK RECEIVER AND INDICATOR.

SPECIFICATION forming part of Letters Patent No. 425,686, dated April 15, 1890.

Application filed July 25, 1889. Serial No. 318,642. (No model.)

To all whom it may concern:

Be it known that I, EDWARD C. MEHLECK, a citizen of the United States, residing at Albany, in the county of Albany, in the State 5 of New York, have invented a new and useful Improvement in Check Receivers and Indicators, of which the following is a specification,

My invention relates to improvements in 10 devices for indicating the amount paid by a customer to the clerk or person in charge of a place of business in such a manner that the amount paid shall be displayed and recorded; and the objects of my invention are to provide 15 an automatic check receiver and indicator that will sound an alarm, open the money-drawer, display to the customer the amount he has paid, and place the checks in separate compartments corresponding to the 20 amount of the sale. I attain these objects by the mechanism illustrated in the accompanying drawings, in which—

Figure 1 is a front elevation; Fig. 2, a section along the line *a b* on Fig. 1. Fig. 3 is a 25 section *f g* on Fig. 2; Fig. 4, a section *f' g'* on Fig. 2, and Fig. 5 is a view of the money-drawer and cash-receiver, showing the manner of locking the same.

Similar letters refer to similar parts throughout the several views.

A represents a cabinet, usually constructed of wood or other suitable material. To the frame *h*, at the upper front part of the cabinet, (see Fig. 2,) extending across the front of the 35 cabinet, is attached by suitable hinges the top of the swinging face *B*. The swinging face *B* is a flat piece of tin, glass, or other solid substance, extending downward a short distance from the top of the cabinet *A* and 40 partly or quite the whole width of said cabinet. Along the lower edge of the swinging face *B*, I paint or mark figures, as shown in Fig. 1, and separate the figures or combination of figures by means of narrow thin pieces 45 of glass, or metal, or other substance, extending forward from the face *B*. I place a strip of glass *C* across the face of the surface *B*, sufficient in width to cover the figures, and attach the same by an adhesive substance to the said narrow pieces of glass extending forward from the face *B*. I have thus formed at the lower edge of the swinging sur-

face *B* a series of slots, each indicated by a figure or combination of figures readily distinguished through a transparent covering *C*. 55 Immediately beneath the surface *B* is placed the ledge *X*, extending outward a short distance from the face *B* when in its vertical position. Upon said ledge is secured by suitable fastening the metal plate *Y*, which extends backward from the face of the cabinet, and is bent at right angles to the ledge a short distance in the rear of the face *B* when that face is in a vertical plane. Through the horizontal portion of the plate *Y*, and in the rear 60 of the ledge *X*, is placed a series of slots corresponding in position to those formed by the glass divisions in front of the surface *B* in such a manner that a check placed in one of the divisions at the lower edge of the surface 65 *B*, resting as it would on the horizontal portion of the plate *Y* when the surface *B* occupies a vertical position, would fall through the corresponding slot in the plate *Y* when the surface *B* is forced backward from the front 70 of the cabinet, as shown in dotted lines in Fig. 2.

Extending across from one side of the cabinet to the other, in the rear of the ledge *X* and extending downward below it, I place a 75 strip of wood *P'*, leaving a space between the front of the cabinet and said strip *P'* and immediately beneath a series of slots *W* in the plate *Y*, through which space a check passing through slots *W* will fall. To the 80 surface of the strip *P'*, toward the front of the cabinet, I place a series of vertical projections, extending across the space between the strip *P'* and the front of the cabinet, corresponding to the divisions between the slots 85 *W* in the plate *Y*.

To the bar *o*, secured to the sides of the cabinet *A* and extending across it in the rear of the face of the cabinet, is secured by suitable hinges *I* the oscillating hopper *E*, so constructed that the forward edge of its lower horizontal portion will rest in contact with the interior face of the cabinet when it is in its normal position, as shown in full lines in Fig. 2; but when said hopper is moved on its 95 hinges *I* its upper portion *n* comes into contact with the face of the cabinet and the lower portion withdraws therefrom, as shown by dotted lines in Fig. 2. The hopper *E* is 100

divided into compartments, corresponding to the divisions along the strip P', by means of the partitions P². (See Fig. 4.)

Below the ledge X and extending downward to the ledge Q, immediately over the money-drawer, I construct the front of the cabinet of glass, painted a dark color, usually black, except immediately in front of each division of the hopper E, which remains unpainted and has upon it simply the figures in black, corresponding to the numerals on the division of the lower edge of the surface B, in the same vertical plane and just above it. Thus when a check is placed in one of the divisions 15 on the lower edge of the swinging surface B, and that surface is pressed backward from the front of the cabinet, the check will fall through the slot in the plate Y, be conducted between the partitions along the strip P', will 20 fall into the corresponding compartment in the hopper E, and will be displayed by forming a white background behind the transparent surface containing the dark or painted figures, which are the same as those on the 25 lower edge of the swinging surface B in the position which the check first occupied.

To the rear of the swinging surface B, I attach the horizontal bar c, which extends backward from the rear of the surface B and 30 carries the grooved stud v, which is secured to the end of the vertical bar d, which vertical bar d is attached by means of the connecting-bars e e to the horizontal portion of the hopper E. The bar d is right angle in 35 form, having a lower horizontal portion k extending toward the rear of the cabinet and connected near its horizontal end, farthest from the vertical part of the bar, with a spiral spring S, which spiral spring S is secured to the horizontal board S' beneath the hopper E. Said board S' extends across the entire cabinet in the rear of the face of the cabinet.

To the rear of the strip P' extends the horizontal guide-bar r, containing the stud t and 45 provided with the slot in the end of the bar between the stud and the end of the bar, through which the vertical portion of the bar, d passes and comes in contact with the stud t. By means of this arrangement of the horizontal bar, attached to the surface B, carrying the stud v at the end of the bar d, the 50 said bar d is forced upward by the movement of the surface B backward, as shown by the dotted lines in Fig. 2. Forcing the bar d upward causes the horizontal portion k of said bar to be forced upward and backward from the front of the cabinet, which draws backward the lower portion of the hopper E and causes the upper portion n of said hopper to 55 come into contact with the surface of the cabinet, thus allowing the check or checks contained in the compartment or compartments of the hopper E to fall downward through a series of slots in the bottom board S' into the 60 check-receiver R of the money-drawer D, and at the same time the check passes through 65 the slot W of the plate Y, along the division

on the strip P', rests upon the upper surface n of the hopper E and is retained there until the resiliency of the spring S causes the swinging surface B and the hopper E to resume their normal position, which occurs immediately upon the force being removed from the surface B. The check then passes into the hopper E and is displayed.

For the purpose of causing an alarm to be made at the time the amount of the sale is displayed, I place the battery F on the bottom board S' at the rear of the cabinet and connect it by suitable wires to the electric bell H, secured to the interior rear surface of the cabinet.

To the bar c, attached to the swinging surface, I place a metal strip s, placed in such a position that when the surface B is pressed backward the strip s will come in contact with the metallic strip G.

The metallic strip G is connected by means of a wire to one of the poles of the battery F. The metallic strip s is connected by means of a wire to the electric bell H. Thus when the metallic strips G and s are brought in contact an electric circuit is formed through the bell and they come thus in contact, when the surface B is pressed backward to allow 95 the checks to fall through the slots in the plate Y, and an alarm is immediately given by the ringing of an electric bell.

In order to open the money-drawer, I attach to the rear of the surface B, at each end thereof, the horizontal inwardly-projecting bars Z Z, to the end of each of which is attached the chain J J, extending downward and toward the rear of the cabinet, and to the lower end of each chain is attached the rear end of the dog L, the dog L being secured by a bolt passing through it near its opposite end to the side of the cabinet. The end of the dog L, to which the chain J J is attached, is in contact with the end of the slot N in the top of the side of the drawer near its rear end. By means of this arrangement, by pressing backward the surface B, the bars Z are raised, lifting the dog L out of the slot N in the sides of the money-drawer, and the spring O in the rear of the money-drawer forces forward the money-drawer. The money-drawer D is placed beneath the bottom board S' and opens outwardly from the front of the cabinet, sliding backward and forward in the opening made 120 for that purpose.

The drawer D is divided by a transverse partition U, separating the drawer into two sections—forward and rear section. The forward section is used for containing the money, and is divided into suitable compartments or receptacles for that purpose. The rear section is the check-receiver, and is divided into a series of compartments by means of longitudinal partitions extending from the bottom 125 of the drawer upwardly. On the interior surface of the back of the check-receiver I paint or mark the figures or combination of figures 130 corresponding to those on the lower edge of

the swinging surface B. Each of these compartments in the check-receiver is placed immediately beneath the corresponding compartment of the hopper E in such a manner 5 that as the check leaves the hopper and falls through the slot in the board S' it will drop into the corresponding compartment of the check-receiver R.

It is advisable not to have the check-receiver 10 opened by the clerk or person in charge of the business, and in order to prevent the opening of that part of the money-drawer I place the locking device T T on each side of the lower ledge of the cabinet, in the forward part of the 15 cabinet, which is a bolt extending through the lower ledge of the cabinet (see Fig. 5) and coming in contact with the side of the drawer. The side of the drawer D is provided with a shoulder x at a sufficient distance back of the 20 front of the drawer to allow the forward section of the drawer D to be drawn out a sufficient distance to use the money-receiving part of the drawer. Then it comes in contact with the bolt J, preventing its being drawn out to 25 a greater distance when said bolt T is in the position shown in Fig. 5. By means of an ordinary lock placed in the lower ledge of the cabinet, by the side of the bolt T, the bolt u of the lock may be caused to pass into the 30 opening w in the side of the bolt T, holding the bolt T firmly and securely in position.

In order to prove the amount of sales made, the bolts T T may be taken out by unlocking them, and the checks found in the compartments of the check-receiver counted, the number in each compartment multiplied by the figures painted upon that compartment, which is the value of each check found therein, and the total amount of the sales may be thus 40 computed, which should correspond with the amount of cash in the drawer D.

The checks which I usually employ in the operation of my device are made of celluloid, bone, or ivory, or other suitable substance, 45 and are white, or nearly so, in color, and have no figures or letters upon them, that being unnecessary when the figures are painted upon the glass where the amounts are displayed. However, I do not intend to limit myself to the use of blank checks, nor to the use of figures painted upon glass in the face of the cabinet, since it is apparent that by placing the figures on the checks and leaving the glass unpainted the amount of the check 50 would be displayed, although not in so satisfactory a manner, possibly, because the checks may be turned in their passage from the surface B into the hopper E in such a manner that the figures would not be shown in their 55 proper position.

I do not limit myself to the glass covering C, attached to the narrow vertical projections along the lower edge of the surface B, since I could place an opaque substance in the position occupied by the glass C, and paint the figures on the face of that substance.

A very material part of my invention is the

arrangement of the hopper E in such a manner that the checks in the hopper pass out by the same movement which introduces another 70 check into the machine, and the amount of the second sale is not displayed until the check denoting the first has passed from sight and an alarm has ceased to ring, and it then remains in the hopper beyond the control of 75 the person in charge of a place of business, and in plain sight until another sale is to be indicated. There is no opportunity to tamper with the checks after they have entered the slot in the plate Y, after they have been placed 80 in their proper division of the lower ledge of the surface B, and before they have entered that slot the alarm is sounded and continues to ring until they have passed therein, calling the attention of the customer to the check 85 and reducing to a minimum the opportunities for defrauding.

My invention is extremely simple in its construction, inexpensive, positive in its operation, and does the work required of it in an 90 extremely satisfactory manner.

What I claim as my invention, and desire to secure by Letters Patent, is—

1. In a check receiver and indicator, a cabinet provided with a swinging surface secured 95 by hinges at its upper edge to the frame of the cabinet, said swinging surface forming the upper portion of the front of the cabinet and provided along its lower edge with a series of divisions formed by vertical outwardly-projecting partitions, said partitions connected by a narrow strip, a plate secured to a horizontal ledge placed beneath said swinging surface and flush with the exterior surface of said narrow strip, said plate provided 100 with a series of slots placed in the rear of said swinging surface, corresponding in position to the divisions contained along the edge of said swinging surface, with a receptacle placed beneath said series of slots, and provided with compartments separated by vertical partitions, said compartments corresponding in position to the slots in said horizontal plate, with a transparent face placed 105 in the front of said cabinet immediately before each of said compartments contained in said receptacle, all substantially as described, and for the purpose as set forth.

2. In a check receiver and indicator, a cabinet provided with an upper swinging surface 110 secured by hinges at its upper edge to the frame of the cabinet, and provided along its lower edge with a series of divisions formed by vertical outwardly-projecting partitions, said partitions connected by a narrow strip, 115 a plate provided with a series of slots secured to the horizontal ledge placed beneath said swinging surface, said slots being placed in the rear of said swinging surface, corresponding in position to the divisions along the edge 120 of said surface, with a receptacle placed beneath said series of slots and provided with compartments separated by vertical partitions, said compartments corresponding in 125 position to the divisions along the edge of said surface, with a receptacle placed beneath said series of slots and provided with compartments separated by vertical partitions, said compartments corresponding in 130 position to the divisions along the edge of said surface.

position to the slots in said horizontal plate, an inwardly-projecting horizontal bar attached to the interior face of said swinging surface, its end connected by a chain to the dog, secured to the side of the cabinet and resting in a notch placed in the top of the side of the money-drawer, the inwardly-projecting bar attached to the interior face of said swinging surface carrying the stud attached by connecting-straps to the horizontal portion of the receptacle, placed beneath the series of slots in the said horizontal plate, said vertical rod provided with a lower horizontal portion attached to a spiral spring, said spiral spring secured to the bottom of the cabinet, a metallic plate attached to said swinging surface, said metallic plate connected by a wire to an electric bell, said electric bell secured to the rear frame of the cabinet and connected to one of the poles of the battery, the opposite pole of the battery connected with a connecting-plate placed in such a position in reference to the metallic plate attached to the swinging surface that when the swinging surface is forced backward the metallic plates come in contact, all substantially as described.

3. In a check receiver and indicator, a cabinet provided with an upper swinging surface secured by hinges at its upper edge to the frame of the cabinet and provided along its lower edge with a series of divisions formed by vertical outwardly-projecting partitions, said partitions connected by a narrow strip, a plate provided with a series of slots secured to the horizontal ledge placed beneath said swinging surface, said slots being placed in the rear of the said swinging surface, corresponding in position to the divisions along the edge of said surface, with a receptacle placed beneath said series of slots, and provided with compartments separated by vertical partitions, said compartments corresponding in position to the slots in said horizontal plate, an inwardly-projecting horizontal bar attached to the interior face of said swinging surface, its end connected by a chain to the dog, secured to the side of the cabinet and resting in a notch placed in the top of the side of the money-drawer, the inwardly-projecting bar attached to the interior face of said swinging surface carrying the stud attached to the end of the vertical rod, said vertical rod attached by connecting-straps to the horizontal portion of the receptacle placed beneath a series of slots in said horizontal plate, said vertical rod provided with a lower horizontal portion attached to a spiral spring, said spiral

spring secured to the bottom of the cabinet, a metallic plate attached to said swinging surface, said metallic plate connected by a wire to an electric bell, said electric bell secured to the rear frame of the cabinet and connected to one of the poles of the battery, the opposite pole of the battery connected with a connecting-plate placed in such a position in reference to the metallic plate attached to the swinging surface that when the swinging surface is forced backward the metallic plates come in contact, all substantially as described.

4. In a check receiver and indicator, a combination of a cabinet A, provided with a receptacle E, attached by hinges to the horizontal bar o, extending across the cabinet from one side to the other, having a lower surface m in contact with the face of the cabinet when said receptacle is in its normal position, when oscillated having its upper surface n in contact with said face, with a transparent plate M placed in the exterior face of the cabinet immediately in front of said receptacle E, all substantially as described.

5. In a check receiver and indicator, a combination of a cabinet A, provided with a drawer D, containing a transverse partition U, extending across said drawer, the rear section R of said drawer divided into compartments by means of a series of vertical partitions, with a lock-bolt T passing through the ledge Q of said cabinet and coming in contact with the top of the side of said drawer D, and engaging with the shoulder x in the top of the side of said drawer, with the spring O attached to the rear of the lower part of the frame of the cabinet A in contact with the rear portion of said drawer D when said drawer D is closed, the top of the side of said drawer being provided near its rear end with a shoulder N, in contact with the dog L when said drawer is closed, all substantially as described.
